BRACKET ARM FOR A LAMP

Henry J. Salvador, Long Beach, Calif., assignor to Eagle
Manufacturing Co., City of Industry, Calif., a corpora-
tion of California

Filed Nov. 29, 1966, Ser. No. 4,849

Term of patent 14 years

(Cl. D48—4)

FIGURE 1 is a perspective view of a bracket arm for a lamp, showing my new design;

FIGURE 2 is a side elevational view thereof; and
FIGURE 3 is a top elevation view thereof.

The bottom of the bracket arm is of conventional
design.

The dominant portion of the design is shown in solid
lines.

The broken line showing of a wall mounting plate is
for illustrative purposes only.

I claim:

The ornamental design for a bracket arm for a lamp,
substantially as shown and described.
